UNITED STATES PATENT OFFICE

2,112,473

SOUND REPRODUCING APPARATUS

Ray E. Tolerton, Fort Wayne, Ind., assignor to
The Magnavox Company, Fort Wayne, Ind., a
corporation of Arizona

Application August 3, 1934, Serial No. 738,302

7 Claims. (Cl. 179—115.5)

This invention relates to electrodynamic sound reproducing apparatus and more particularly to an improved supporting and centering means for the apex and actuating coil of a conical diaphragm 5 of the type commonly used with apparatus of this character.

An object of the invention is to provide a new and improved centering support or spider for the diaphragm and actuating coil of an electrodynamic 10 sound reproducing device which can be secured directly to the magnetic field structure without the interposition of special supporting means.

Another object of the invention is to provide a new and novel coil centering and supporting 15 spider for apparatus of the above character which is simple and practical in construction and efficient in operation.

In the past, where the diaphragm and actuating coil centering support has taken a symmetrical and annular form, it has been the practice 20 to provide a separate supporting plate, upon which the coil centering support can be mounted. An example of such an arrangement is shown in Edwin S. Pridham, United States Patent Number 25 1,886,735, dated April 8, 1932, and assigned to the assignee of this application for patent. In this prior patent the diaphragm and coil centering support has inner and outer annular portions which are connected together by spirally disposed 30 flexible arms. The inner annular portion of this support is secured to the diaphragm assembly and the outer annular portion thereof is fixed upon an outwardly disposed flange, carried by a supporting plate, which is adjustably secured upon 35 the magnetic field structure. In this way the supporting plate forms a continuous annular support about the diaphragm actuating coil, to which the outer portion of the diaphragm and coil centering support can be attached.

An annular diaphragm and coil centering support 40 is capable of providing a uniform flexibility throughout its circumference if its outer periphery is supported at uniformly spaced points, as disclosed in the above patent. However, the provision of a symmetrical support for a diaphragm and coil centering means of this character complicates the assembly and otherwise adds to the cost thereof. Therefore, a further object of the 45 invention is to provide a flexible annular diaphragm and coil centering support of novel construction which may be secured directly to the apparatus without requiring an extra supporting plate when the support is disposed outside of the 50 diaphragm, or an extension upon the pole piece

when the support is disposed inside of the diaphragm.

Other objects and advantages of the invention will be in part pointed out and in part evident to those skilled in the art as the description thereof 5 proceeds.

For a better understanding of the invention reference should be had to the accompanying drawing wherein there are shown, by way of illustration and not of limitation, preferred embodiments thereof.

In the drawing:

Figure 1 is a fragmentary vertical sectional view taken along line I—I of Figure 3,

Figure 2 is a perspective view showing a so-called outside centering spider of the type contemplated by this invention,

Figure 3 is a fragmentary front elevation of a loud speaker with a portion of the diaphragm broken away to disclose the details of construction,

Figure 4 is a fragmentary sectional view showing a preferred manner of securing the centering spider to the magnetic field structure,

Figure 5 is a perspective view of a clamping plate,

Figure 6 is a fragmentary sectional view showing the manner of attaching the actuating coil terminal leads to the centering spider, and

Figure 7 is a view similar to Figure 1 showing the invention embodied in a so-called inside centering spider.

In the drawing the diaphragm supporting and centering spider, contemplated by this invention, is shown as applied to an electrodynamic sound 35 reproducing device of the type having a truncated conical diaphragm which is adapted to be actuated by a cylindrical coil secured at the apex thereof. As here shown, the numerals 10 and 11 40 designate respectively the inner and outer poles of a magnetic field structure. Secured upon the outer pole 11 of the magnetic field structure, there is a diaphragm supporting housing 12, to which the periphery of a conical diaphragm 13 is attached. At the apex of the diaphragm 13, there 45 is a cylindrical coil support 14 which carries a diaphragm actuating coil 15. The diaphragm actuating coil 15 is disposed in an air gap formed between the poles 10 and 11 and is adapted to move the diaphragm axially to reproduce sound 50 when a source of modulated current is connected thereto.

In order to hold the cylindrical coil support 14 and the diaphragm actuating coil 15 concentric within the air gap and at the same time permit 55

a limited axial movement thereof, the diaphragm assembly, which includes the diaphragm 13, the cylindrical coil support 14 and the actuating coil 15, is provided at its small end with a flexible centering support or spider designated generally by the numeral 16.

As shown in Figure 2 of the drawing, the flexible centering support or spider 16, in its preferred form, has a rigid flat portion 17 which is adapted 10 to be secured upon the outer pole 11 and a raised annular portion 18 that is secured to the diaphragm assembly. The raised annular portion 18 is formed integral with the rigid flat portion 17 by pressing it outwardly therefrom so as to provide 15 a continuous cylindrical connecting web portion or flange 19 therebetween. In addition to being pressed out, as above, the raised annular portion 18 is rendered flexible by cutting out portions thereof so as to provide a plurality of 20 non-radial connecting arms 20 that extend between the cylindrical portion or flange 19 and a part 21 of the raised annular portion 18 which is adapted to engage the diaphragm assembly.

For stiffness and to provide for a firm gluing 25 of the flexible centering support 16 to the diaphragm assembly, the part 21 of the raised annular portion 18 is provided with a flanged edge 22. The centering support or spider 16 will preferably be made in one piece and of material 30 which can be easily molded or pressed into the configuration desired. The material must also be of such a character that it will permanently hold its shape and not be broken by a frequent flexing of portions thereof when in operation. 35 Such a material can be provided by impregnating a sheet of fabric with phenolic condensate. A sheet of this material can be formed, as above, while the phenolic condensate is plastic and then baked. After baking the device will possess the 40 strength and flexibility required for a centering support of the character described. If the centering support 16 is formed of the above material and in the above manner, it will be necessary to first form the rigid flat portion 17 with the raised 45 annular portion 18 blank and then punch or cut out parts thereof to form the non-radial connecting arms 20 which impart flexibility to the latter portion. The securing holes in the rigid flat portion 17 and the opening for the cylindrical 50 coil support 14, defined by the flanged edge 22, may also be punched or cut out at the same time. In addition to the non-radial connecting arms 20, the raised annular portion 18 will be provided with a suitable extension 23, upon which terminals, for the ends of the coil 15, may be 55 secured.

After the centering support or spider 16 has been formed and secured to the diaphragm assembly, as shown in Figure 1 of the drawing, 60 it is positioned upon the end of the magnetic field structure, together with the diaphragm, and there secured, as shown in Figure 3 of the drawing, by means of four screws 24 which are preferably threaded into slightly raised bosses 25 formed upon the diaphragm supporting housing 12.

As illustrated in Figure 4 of the drawing, the provision of the bosses 25 upon the housing 12 avoids the necessity for drilling into the outer 65 pole 11. However, it is to be understood that the rigid flat portion 17 of the centering support 16 may be secured directly upon the outer pole 11, if desired. In order to prevent a distortion or a twisting of the centering support or spider 16 70 by a tightening of any one of the screws 24,

there is an arcuate clamping plate 26 having a hole at each end, through which a screw 24 may pass. This clamping plate 26 is dished upwardly between its ends so that no rattle will be set up by a striking of the parts should the centering support 16 vibrate. A preferred form of clamping plate 26 is shown in detail in Figure 5 of the drawing.

As shown in Figure 6 of the drawing, each end 10 of the diaphragm actuating coil 15 is brought out and soldered to a suitable metallic terminal 27, carried by the extension 23, formed upon the inner portion 21 of the centering support 16. Extending outwardly from each of the terminals 27 is a flexible lead 28 which connects through a 15 terminal board (not shown) with a source of modulated current as, for instance, the output transformer of a radio set or a thermionic tube amplifier. The flexible lead 28 is bowed out slightly so as not to interfere with the free flexing 20 of the non-radial connecting arms 20 and is securely fastened to the cylindrical portion or flange 19, of the centering support 16, by a suitable tie 29 which passes through small holes 30 formed therein. 25

With the above arrangement it will be seen that the cylindrical portion or flange 19, upon the rigid flat portion 17, will form a rigid continuous circumferential support for the raised annular portion 18 and permit the non-radial connecting 30 arms 20 to flex uniformly and hold the diaphragm actuating coil 15 concentric within the air gap under all conditions of operation. In other words, the rigid flat portion 17 will be reinforced by the cylindrical portion or flange 19 so that no flexing 35 will take place in the centering support or spider 16, except that which is provided for by the non-radial connecting arms 20.

While the invention has been described above in connection with a centering support or spider 40 of the so-called outside type, it can also be embodied in a centering support or spider of the so-called inside type. An adaptation of the invention to a centering support or spider of this latter type is illustrated in Figure 7 of the drawing. 45 In this figure of the drawing a diaphragm 31 is shown with an attached coil support 32 disposed between the poles 10 and 11 of the magnetic field structure. In this instance, the diaphragm coil support 32 is held concentrically 50 within the air gap by a flexible centering support or spider 33 which is secured directly upon the end of the pole 10, rather than upon an extension or abutment such as is customarily provided with a so-called inside flexible centering support. The flexible centering support 33 is 55 pressed or molded with an integral inwardly extending cylindrical portion 34 that terminates with a flat end portion 35, through which a screw 36 is threaded into the pole 10. At its outer periphery the flexible centering support 33 has a circumferential flange 37 and located between the top of the cylindrical portion 34 and the circumferential flange 37 there is a plurality of non-radial and flexible connecting arms 38. These 65 connecting arms 38 may take any desired shape. For example, they can be like the arms 20 of the previously described centering support 16. With this latter type of centering support, the abutment which is usually turned upon the inner pole 70 10 may be dispensed with, and as a result the possibility of magnetic leakage at this point is eliminated.

Having thus described my invention, I desire to have it understood that this invention is not 75

limited to the specific means disclosed, but may be embodied in other ways that will suggest themselves to persons skilled in the art. It is believed that this invention is new and it is desired to 5 claim it so that all such changes as come within the scope of the appended claims are to be considered as part of this invention.

Having thus described my invention, what I claim and desire to secure by Letters Patent is—

- 10 1. The combination of a conical diaphragm of the type having a cylindrical actuating coil at the apex thereof, and a unitary support for said diaphragm comprising a member of mouldable non-metallic material having an outer flat portion, an annular upstanding flange formed centrally thereupon, and a plurality of flexible arms extending inwardly from the top of said flange and forming an axially yielding support for the small end of the conical diaphragm.
- 20 2. The combination of a conical diaphragm of the type having a cylindrical actuating coil at the apex thereof, and a support for said diaphragm and actuating coil comprising a single member of hot pressed mouldable material having an outer flat portion, an upstanding cylindrical flange formed centrally thereupon, and an inner flat portion extending from the top of said flange and having a plurality of flexible arms forming a means for axially centering the small end of a 25 conical diaphragm and the actuating coil.

30 3. A centering support for a conical diaphragm of the type having a cylindrical actuating coil at the apex thereof, comprising an integrally formed member of non-metallic mouldable material having an outer support engaging portion extending in a plane transverse to the axis of the diaphragm, and an inner diaphragm engaging portion formed in a plane parallel with but displaced from the plane of said outer support engaging portion, said outer and inner portions being connected together by a cylindrical connecting web formed therebetween and extending concentric to the axis of the diaphragm.

4. A centering support for a conical diaphragm 45 of the type having a cylindrical actuating coil at the apex thereof, comprising a unitary member of thermoplastic material having a flat portion disposed in one plane adapted to engage a supporting means adjacent the cylindrical actuating coil, and a second flat portion formed in a plane displaced axially from but parallel with the plane of said first portion having flexible arms adapted

to be secured to the diaphragm, said flat portions being formed concentrically with respect to each other upon opposite sides and at opposite ends of an integrally formed cylindrical connecting web.

5. A centering support for a conical diaphragm 5 of the type having a cylindrical actuating coil at the apex thereof, comprising a centering member constructed in one piece of a mouldable non-metallic material having a rigid cylindrical portion adapted to be disposed concentric to the axis of the diaphragm, a transversely extending portion of flexible configuration at one end of said rigid cylindrical portion adapted to engage the diaphragm adjacent its actuating coil, and a second transversely extending portion at the other 15 end of said cylindrical portion extending in a plane parallel with said flexible portion and adapted to be secured upon a fixed support.

6. A centering support for a conical diaphragm 20 of the type having a cylindrical actuating coil at the apex thereof, comprising an integral member of mouldable phenolic condensate having an integrally formed cylindrical reenforcing portion adapted to be secured concentric to the axis of the diaphragm, outwardly extending portions at one 25 end of said cylindrical portion adapted to secure said cylindrical portion upon a fixed support, a web of said mouldable material across the other end of said cylindrical portion having parts cut away to form flexible arms, and a cylindrical 30 flange formed upon said web concentric with said reenforcing portion adapted to be secured to the diaphragm adjacent its actuating coil.

7. In a loudspeaker the combination of a magnetic field frame having an annular air gap there- 35 in, a conical diaphragm supported upon said field frame having a coil at the small end thereof disposed in said air gap, and a support for centering said field coil in said air gap comprising a one-piece non-metallic member having concentric 40 transversely extending portions disposed in spaced parallel planes and connected together by a cylindrical portion extending concentric to the axis of the diaphragm, one of said concentric transversely extending portions being adapted to 45 be secured upon the magnetic field frame, the other of said concentric transversely extending portions being located in outwardly spaced relation from said field frame engaging portion and adapted to be secured to the diaphragm. 50

RAY E. TOLERTON.
